UNITED STATES PATENT OFFICE.

EMILE HARTMAN, OF BROOKLYN, E. D., NEW YORK, ASSIGNOR TO L. DRYFOOS & CO., OF NEW YORK CITY.

IMPROVEMENT IN MACHINES FOR PRINTING FABRICS OF CIRCULAR FORM.

Specification forming part of Letters Patent No. 176,626, dated April 25, 1876; application filed April 27, 1869.

To all whom it may concern:

Be it known that I, EMILE HARTMAN, of Brooklyn, E. D., county of Kings, State of New York, have invented a certain new and useful Machine for Printing Circular and Analogous Shapes; and I do hereby declare the following is a full and exact description that of the same, reference being had to the accompanying drawing, being part of this specification.

Similar letters of reference indicate like parts in the several figures.

Figure 1 is a side elevation of my machine. Fig. 2 is a cross-section on line S S, Fig. 1, looking toward the left.

My printing-machine is designed to print ornaments on circular shapes, such as the conical surface of ladies' skirts, collars, or the like, in which case the surface to be printed is that of a truncated cone, or nearly so, which is, when developed, a surface bounded on two opposite sides by concentric circles, and on the other two sides by radial lines.

The nature of my invention consists in the use of a conical roller, which has the ornament to be printed engraved on its surface, and a press-roller also conical, both of such a taper that the surface to be printed, the developed surface of a truncated cone, when entered between these rollers with one of its radial sides, will be drawn through and be printed without drawing too much on one side or the other.

For this purpose it is necessary that the two conical rollers be constructed in such a manner that their vertexes meet in one point, whereby any shifting of any one point on one roller on the line of contact over the corresponding point of the other roller, causing the one point to travel faster than the other, is prevented, and a true rolling motion produced.

The printing of such ornaments has been till now done by blocks and by hand, but with my machine, and a number of circular surfaces joined by suitable means, a great saving of labor and time will be effected.

By making the printing-roller of any de-

sired irregular form, and shaping the press-roller in such a manner that constantly a true rolling motion along the line of contact is effected, any other shape than conical may be printed.

A A¹ are the two side frames carrying the bearings of the printing-roller B, the press-roller C, and the ink or color roller D. A² is the foundation-plate; A³, a cross-bar connecting the two side frames A A¹ at the top.

The bearings of the press and ink rollers are constructed in such a manner as to adapt themselves to any form of print-roller the taper and diameter of which will change according to the form of the circular shape to be printed, and the design on the same. For this purpose the pillow blocks or bearings E E' are provided with trunnions e e', which can travel up and down in a slot in the side frames. By these means they are able to adapt themselves to any radial position the journals of the press-roller may occupy. The bearings f f' of the color-roller are constructed in the same manner as shown in the drawing.

G G' are screws that force the press-roller down on the print-roller with the desired pressure. H H' are screws that force the color-roller up against the print-roller. I is the color-box. J is a pulley or gear secured to the shaft of the print-roller, giving the latter its revolving motion. K is the scraping-plate, turning on the centers k k', and held in close contact to the surface of the printing-roller by weighted levers L L', thereby removing all the surplus color from the printing-roller.

At M is shown the engraved design which takes up the color and transfers it to the cloth that passes through between the print and press rollers.

The press-roller C is covered with cloth, rubber, or any other elastic material N. The print-roller B is either all of copper or of cast-iron covered with copper.

It will now be readily understood that after the cloth is entered between the two conical rollers, and drawn through, that the

cloth will travel faster at the large end of the cones than at the small, and that a circular surface will be printed. Having now fully described my invention, what I claim as new therein, and desire to secure by Letters Patent, is—

The combination of a conical printing-roller and a conical impression-roller, operating together, substantially as and for the purposes set forth.
